United States Patent Office.

FREDERICK W. DAVIDSON, OF CLEVELAND, OHIO.

Letters Patent No. 96,782, dated November 16, 1869.

IMPROVED MACHINE FOR ROLLING CAR-COUPING PINS.

The Schedule referred to in these Letters Patent and making part of the same.

I, FREDERICK W. DAVIDSON, of Cleveland, in the county of Cuyahoga, and State of Ohio, have invented certain Improvements in a Mill for Rolling Shackle or Car-Coupling Pins, of which the following is a specification.

The nature of this invention relates to the construction of a mill for rolling shackle or car-coupling pins directly into bars, the pins being formed with heads having eyes for attaching a chain.

Figure 1 is a side elevation.

Figure 2 is a vertical cross-section.

In the accompanying drawings—

A represents a frame for supporting the rollers B B, which rest on a suitable bed-plate, C.

In the frame A are the boxes d, for the rollers B B.

On the top of the frame there is a bar, e, and screws e' e', which hold the boxes in place.

The rollers are connected by gear-wheels g g.

The rollers B B, as will be seen in fig. 1, have grooves a a around them, which are formed at proper intervals required for the length of pins, with a space, a', larger than the groove, and broad enough to make a head to the pin.

Within this space is a pointed projection, b, which punches a hole in the head, and at the same time spreads the metal into the space a', thus forming the head. The two rollers being alike, the projections and spaces meeting produce this result.

The projections b may have a hole through them, in the lower roller, as seen in fig. 2, so that a small portion of the metal may be cut and pass into the centre of the rollers, which are hollow.

The grooves at a', near the head-space, are reduced in size to form a point to the pins, but do not cut them entirely in two, so that the pins are rolled out into long bars, and may be broken apart as may be wanted.

Other grooves, c c, in the rollers, larger than the grooves a a, are for first reducing the iron into bars before passing them through the grooves a a, and the grooves may be round or flat, as represented.

By the use of a rolling-mill, of the construction described, shackle-pins used in coupling railway-cars may be very rapidly and perfectly made, at a much less cost in time and labor than in the ordinary way.

I claim, as my invention—

The rollers B B, having grooves a a formed around them, with the spaces a' and projections b to form the heads, and the projections a' to form the points on shackle-pins, substantially in the manner shown and for the purpose set forth.

FREDERICK W. DAVIDSON.
